UNITED STATES PATENT OFFICE

100,017

DESIGN FOR A COMBINATION STORAGE AND REFRIGERATOR CABINET

Lionel J. Gottschalk, New Orleans, La.

Application October 9, 1935, Serial No. 58,904

Term of patent 3½ years

To all whom it may concern:

Be it known that I, Lionel J. Gottschalk, a citizen of the United States, residing at New Orleans, in the Parish of Orleans and State of Louisiana, have invented a new, original, and ornamental Design for a Combination Storage and Refrigerator Cabinet, of which the following is a specification, reference being had to the accompanying drawing, forming part thereof.

The figure is a perspective view of a combination storage and refrigerator cabinet, embodying my new design.

I claim:

The ornamental design for a combination storage and refrigerator cabinet, as shown.

LIONEL J. GOTTSCHALK.
